UNITED STATES PATENT OFFICE.

VOLENTINE L. NEY AND JACOB NEY, OF CANTON, OHIO.

HAY-ELEVATOR TRACK.

SPECIFICATION forming part of Letters Patent No. 395,714, dated January 8, 1889.

Application filed May 23, 1888. Serial No. 274,844. (No model.)

To all whom it may concern:

Be it known that we, VOLENTINE L. NEY and JACOB NEY, citizens of the United States, residing at Canton, in the county of Stark 5 and State of Ohio, have invented certain new and useful Improvements in Hay-Elevator Tracks; and we do hereby declare that the following is a full, clear, and exact description of the same, reference being had to the 10 annexed drawings, making a part of this specification, and to the letters and figures of reference marked thereon, in which—

Figure 1 is a top view showing the different parts of the track placed in proper position. Fig. 2 is a side view showing a hay-elevator carriage located thereon. Fig. 3 is a detached view of one of the securing-blocks and its key or wedge. Fig. 4 is a transverse section of the track and longitudinal section 20 of the securing-block, showing the traveling wheels located on the track. Fig. 5 is a detached view of a supporting-hook.

The present invention has relation to hay-elevator tracks; and its nature consists in the 25 different parts and combination of parts hereinafter described, and particularly pointed out in the claims.

Similar letters of reference indicate corresponding parts in all the figures of the drawings.

In the accompanying drawings, A represents the rails of the track proper, which are located substantially as illustrated in Figs. 1 and 4. These rails are cut or formed of any 35 desired length, and, as shown, they consist of the vertical and rounded portions, said portions being formed the proper size, so as to give the track proper the desired amount of strength.

It will be understood that the rounded portions of the rails A are for the purpose of providing a traveling surface for the traveling 40 wheels of a hay-elevator carriage.

The rails A are placed parallel, as illustrated in Fig. 1, and are held the proper distance apart by means of the securing-blocks B. For the purpose of suspending the track proper, a sufficient number of the securing-blocks B are provided with the extension or

arm a, which is provided with the aperture a', to receive the hooks b or their equivalent.

In case it is desired to provide a securing-block at a point where it is not necessary to support or hold the track, or at a point 55 where it is desired to form a joint, the extension or arm a may be dispensed with, as illustrated in Fig. 1. It will be understood that joints can be formed at places where the securing-block having the extension or arm 60 a is located equally as well as without said extension or arm.

The securing-blocks B are provided with the grooves or notches b', which are for the purpose of receiving and holding the vertical 65 portion of the rails A, as illustrated in the drawings. At places where it is desired to form a joint the meeting ends of the rails A are placed in one of the grooves or notches b', and the securing-block so adjusted that it 70 will embrace one end of each of the meeting rails. It will be understood that but one of the rails A should be jointed at a single place in the track proper, so as not to weaken the track. The securing-blocks B are provided 75 with the openings C, which are for the purpose of receiving the key or wedge D, as illustrated in Figs. 1 and 4. The key or wedge D is for the purpose of expanding the securing-block B, thereby securely holding 80 the rails A in the grooves or notches b'.

The securing-blocks B should be formed of malleable iron or like material, so that they will not break as they are expanded by the key or wedge D. The securing-blocks B are 85 provided with the ribs e, which are located substantially as illustrated in the drawings, and are for the purpose of assisting in holding the rails A in proper position.

It will be seen that a track constructed as 90 above described can be formed without drilling the rails, and at the same time a strong track can be produced without any riveting.

Having fully described our invention, what we claim as new, and desire to secure by Letters Patent, is—

1. The securing-blocks B, provided with the grooves or notches b', the ribs e, and the open-

ings C, the key or wedge D, and the rails A, substantially as and for the purpose specified.

2. The securing-blocks B, provided with the openings C and the grooves or notches b', the key or wedge D, the rails A, and means for suspending the rails, substantially as and for the purpose specified.

In testimony that we claim the above we have hereunto subscribed our names in the presence of two witnesses.

VOLENTINE L. NEY.
JACOB NEY.
